UNITED STATES PATENT OFFICE.

HAROLD ROHRDANZ AND ARCHIBALD G. MATTESON, OF LOS ANGELES, CALIFORNIA;
SAID MATTESON ASSIGNOR TO CHARLES J. KOKEN, OF LOS ANGELES, CALIFORNIA.

MOTION-PICTURE-FILM-SPlicing MACHINE.

Application filed October 5, 1921. Serial No. 505,633.

To all whom it may concern:

Be it known that we, HAROLD ROHRDANZ, residing at 1034 West Thirty-fourth Street, Los Angeles, in the county of Los Angeles, 5 State of California, and ARCHIBALD G. MATTESON, residing at 5253 South Figueroa Street, Los Angeles, in the county of Los Angeles and State of California, both citizens of the United States, have invented a 10 new and useful Motion-Picture-Film-Splicing Machine, of which the following is a specification.

Our invention relates to improvements in motion picture film splicing machines in 15 which the broken film when located in the machine, is perfectly aligned, both broken ends are trimmed or sheared simultaneously by a double cutting shear with one movement, leaving exposed the necessary amount 20 of film which is cleaned of the sensitive photographic material by the use of a special scraping tool, after which the adhesive is applied and the same movement which 25 clamps the joint together also measures and retains perfect pitch of the perforations along the edge of the film.

We attain these objects by the mechanism illustrated in the accompanying drawing, in which—

30 Figure 1 is a plan view of the entire machine; Fig. 2 is a view in perspective of the scraping tool used to clean the film preparatory to applying the adhesive by which the splice in the film is secured.

35 Similar letters apply to similar parts throughout.

The base plate A, to which four standards or blocks B, are secured one at each of the four corners, and which standards or blocks 40 carry two rods or slides C, and C¹, constitute the frame of the machine.

45 On rod C is attached plate a, which is held permanently in position by clamp screw to rod C¹. In plate a, is located four aligning pins b, two of which project through the rack perforations of film F, and two located at sides of film.

50 The film clamping plate D, hinged on rod C, is clamped down on film F, and held by spring latch 1.

55 The shear-plate S, hinged to rod C¹, trims both broken ends of film simultaneously, shown by dotted lines, shearing down by shear blocks e, and e¹, which are secured to base plate A.

The spring clamp f, secured to shear plate S, automatically holds exposed end of film while being sheared or trimmed. Shear knife plate S¹, made of tool steel, is secured to plate S, which provides for re- 60 newal of shear knife.

The plate g, hinged to rod C, contains four aligning pins b, two projecting through the rack perforations of film and two located at edge of film. Clamping plate h, 65 hinged to rod C is clamped down and held over film by spring latch 1—3, in the same manner film clamping plate D holds the opposite broken end of film while shear S is swung over and down, trimming both 70 ragged ends of film simultaneously. After shearing, shear S is returned to position shown in drawing.

A serrated tool i, Fig. 2 is used to clean the photographic substance from the film 75 on the exposed end of film over shear block e¹, after which adhesive is applied to secure splice in film.

Referring to plate g, upon which has 80 been located the broken film and the clamping plate h clamped down over film by latch 1—3 the next operation releases the latch and both plates g and h are lifted, together, carrying film to opposite exposed end of film over shear block e¹, by sliding 85 along on rod C to position against shear block e¹, when the two ends of film are clamped down together sufficient time to dry cement, being held in this position by latch 1—2, after which clamping plates D 90 and h are lifted and the completed splice is accurately finished.

We are aware that prior to our invention film splicing machines have been made. We therefore do not claim such a combination broadly; but 95

We claim—

1. A film trimming and splicing device comprising a pair of spaced stationary shear blocks, a pivoted shear adapted to 100 cooperate with both of said shear blocks to effect a shearing action, means for holding a length of film with an end portion to be trimmed extending over one of said shear blocks, a movable film holding means to 105 hold a second length of film with an end portion to be trimmed extending over the other shear block, and a guide rod on which said last named film-holding means is pivotally and slidably mounted, said movable 110

film-holding means being adapted to be advanced on said rod and to be swung vertically thereon whereby the end portion of the film carried thereon may be brought 5 downward upon the end portion of the film in the other film holder.

2. A film trimming and splicing device comprising a pair of spaced stationary shear blocks, a pivoted shear adapted to 10 cooperate with both of said shear blocks to effect a shearing action, means for holding a length of film with an end portion to be trimmed extending over one of said shear blocks, a movable film-holding means 15 adapted to hold a second length of film with an end portion to be trimmed extend-

ing over the other shear block, a guide rod on which said last named film-holding means is pivotally and slidably mounted, said movable film-holding means being 20 adapted to be advanced on said rod and rockable vertically whereby the end portion of the film carried thereon may be brought downward upon the end portion of the film in the other film holder, said movable film 25 holder embodying a table and a leaf adapted to swing independent of each other on said rod and to be moved collectively thereon.

ARCHIBALD G. MATTESON.
HAROLD ROHRDANZ.
